US0D1002642S

(12) **United States Design Patent** (10) **Patent No.:** **US D1,002,642 S**
Mistry et al. (45) **Date of Patent:** **** Oct. 24, 2023**

(54) **DISPLAY SYSTEM WITH GRAPHIC USER INTERFACE**

(71) Applicant: **Samsung Electronics Co., Ltd.**, Gyeonggi-do (KR)

(72) Inventors: **Pranav K. Mistry**, Saratoga, CA (US); **Jiawei Zhang**, Los Gatos, CA (US); **Seungsu Hong**, Seoul (KR); **Abhijit Z. Bendale**, Campbell, CA (US)

(73) Assignee: **SAMSUNG ELECTRONICS CO., LTD.**, Gyeonggi-Do (KR)

(**) Term: **15 Years**

(21) Appl. No.: **29/765,737**

(22) Filed: **Jan. 11, 2021**

(51) LOC (14) Cl. **14-02**

(52) U.S. Cl.

USPC **D14/307**; D20/10; D6/675

(57) **CLAIM**

The ornamental design for a display system with graphic user interface, as shown and described.

DESCRIPTION

FIG. 1 is a front perspective view of a display system with graphic user interface, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof;

FIG. 8 is a rear perspective view thereof; and,

FIG. 9 is another rear perspective view thereof.

The broken lines show environmental elements that form no part of the claimed design.

1 Claim, 9 Drawing Sheets
